UNITED STATES PATENT OFFICE

2,209,008

MOUNTING FOR ELECTRIC FIXTURES

Alexander K. Sutherland, Milwaukee, Wis., assignor to Moe-Bridges Corporation, Milwaukee, Wis., a corporation of Wisconsin

Application October 1, 1938, Serial No. 232,837

2 Claims. (Cl. 240—133)

This invention relates to mountings for electric fixtures such as light fixtures, and it has among its objects a light fixture mounting equipped with a simple and cheap clamping support for a globe or similar hollow enclosure forming a part of the assembled fixture so as to permit quick and easy removal of the enclosure from its permanent position for cleaning or exchanging, and quick and simple clamping of the enclosure in its location.

The foregoing and other objects of the invention will be best understood from the following description of exemplifications thereof illustrated in the accompanying drawing, wherein

Fig. 1 is a vertical sectional view of a lighting fixture mounting exemplifying the invention;

Fig. 2 is a view along line 2—2 of Fig. 1 with parts of the globe and the cam extension broken away;

Fig. 3 is a view along line 3—3 of Fig. 1;

Fig. 4 is a top view of the central portion of the fixture; and

Fig. 5 is a view similar to Fig. 1 illustrating another exemplification of the invention.

Referring to Figs. 1 to 3, an electric fixture, such as a lamp, is supplied through an electric cord 11 looped through a supporting chain 12, attached to the ceiling for instance, for carrying a socket support in the form of a U-shaped bail 30 to which is clamped a lamp socket 14 holding the lamp bulb 15 which is energized by the cord 11.

The lamp is enclosed by an enclosure, such as a translucent globe 16, which is carried by a clamping member in the form of a sheet metal shell 17 slidably mounted on the socket supporting bail wires 13 and provided with a flanged rim portion 18 against which the border 19 of the globe is held clamped by a plurality of pivotally mounted clamping arms 21. Each clamping arm 21 is formed of a wire bent to assume the U-shaped formation shown in Figs. 1 and 2, the ends of the wire being outwardly bent to form pivot projections 22 which are pivoted on the side portions of re-entrant U-shaped loops 24 formed in a split annular spring wire 25 shaped and compressed to the form shown in Fig. 3 so as to remain clamped under its spring action within the retainer groove 26 formed adjacent the periphery of the top wall of the shell.

The freely swinging clamping arms 21 rest against a cam edge surface 27 of a cam member 28 in the form of a sheet metal cup extending from the socket support 13 of the lamp fixture, being, for instance, secured to the socket support

by screws 29. In the position shown in Fig. 1, the cam surface 27 forces the clamping arms 21 against the shell rim 18 for clamping the border of the globe. On lifting the slideable shell on its bail support 13, the cam surface 27 of the cam extension 28 releases the clamp-arms 21 from their clamping engagement shown in full lines in Fig. 1 to the free dotted line position in which the globe is entirely released from its clamping engagement with the rim 18 and the arms 21, and may be quickly and simply removed. On the removal of the globe, the clamping shell 17 will drop on its sliding bail support and the cam surface of the socket support extension 28 will swing the clamping arms from the dotted line position 21' to their full line clamping position 15.

After the lamp has been replaced or the interior of the fixture or globe cleaned, the globe may be quickly replaced by simply lifting the clamping shell 17 on its bail support 13, and this upward movement of the clamping shell causes the clamping arms 21 carried by the shell 17 to be lifted to the dotted line position 21'. Thereupon, the globe may be easily positioned against the clamping rim 18 of the clamping shell 17, and the clamping shell is lowered while simultaneously the socket cam extension 27 forces the clamping arms 21 to their clamping position in which they clamp the border of the globe to the rim of the shell; serving to hold the clamping shell 17 and its clamping arms 21 in lower clamped position shown in Fig. 1.

The shell 17 may be locked in its clamping position shown in Fig. 1, by a circular latch member 3 of sheet metal rotatably mounted on the circular edge portion of its bail guide slot in the way shown in Fig. 4 so as to engage a lock projection 4 pressed out from one of the bail wires 13. The latch 3 has a grip arm 5 for turning it till its slot 6 is brought into alignment with the lock projection 4 for releasing the shell 17.

This cooperative relation between the clamping shell 17 with its clamping arms 21 and the socket support with its cam extension 28, makes it possible to utilize thus the weight of the shell for automatically retaining the clamping elements in the clamped position while assuring easy quick removal of the globe as well as clamping of the globe in its assembled position. Since all the elements cooperating in securing the clamping action are freely slideable relative to each other, and the clamping arms are freely suspended to swing between the outer cam surface extension of the socket support and the

clamping rim of the clamping shell, no entanglement or jamming of the clamping elements can take place while removing or mounting the globe in its place.

5 In Fig. 5 is shown another exemplification of the invention. On a ceiling canopy 30 of an electric ceiling fixture, suitably secured over the ceiling outlet, is provided a socket support 31 on which is mounted a socket 14 with an electric bulb 15 as in Fig. 1. A globe clamping member in the form of a metallic shell 33 is slidably mounted on the socket support 31 for movement from the downward full line position to the upward dotted line position 33'. The clamping shell carries on 10 a wire spring 25, similar to that of Fig. 1, a plurality of wire clamping arms 21 for clamping the globe 16 between the clamping rim of the clamping shell 33 and the three ends of the clamping arms 21. As in the arrangement of 15 Fig. 1, the socket support 31 is provided with a cam extension 28 having a cam edge 27 which slidably engages the clamping arms 21 so as to force them to the full line clamping position shown in Fig. 5 when the clamping shell is in its 20 downward position and to release the clamping arms to the dotted line position and permit easy and quick removal of the globe from the lamp fixture when the clamping shell 33 is lifted along its sliding engagement surface with the socket support 31 to the dotted line position.

30 A latch projection 7 of a latch spring riveted to the socket support 31 at 8 extends through a slot 9 of the shell 33 to automatically lock the shell when it is lowered to its clamping position 35 shown in Fig. 5 and to release the shell when the latch projection 7 is pressed inwardly.

Many other modifications of the invention will suggest themselves to those skilled in the art. It is accordingly desired that the appended claims 40 be given broad construction commensurate with the scope of the invention.

I claim:

1. In a mounting for electric light fixtures or the like, a forwardly projecting support, a hollow 45 clamping member slidably movable on said support between a rearward and a forward position, and having a clamping rim for clamping engagement with the border of a hollow enclosure extending around the space in front of said support, a deformed spring member loop clamped by its outwardly acting spring force against a portion of the inner surface of said clamping member, a plurality of clamping arms pivotally carried by peripherally spaced portions of said

5 spring member so as to swing freely in radial directions when the clamping member is in its rearward position, and a cam member extending from said support having an exposed peripheral cam surface arranged to slidably engage and radially press the inner surfaces of said arms so as to swing them outwardly toward said rim during forward sliding motion of said clamping member on said support, said support, said clamping member, and the associated cam surface and clamp arm elements being so shaped and arranged as to force said arms toward said clamping rim for clamping said enclosure border when said clamping member is in the forward position on said support, and to release said arms 10 from their clamping position and permit the free removal of said enclosure from its clamping engagement when said clamping member is slid toward its rearward position on said support.

2. In a mounting for electric light fixtures or the like, a downwardly projecting support, a hollow 20 clamping member slidably movable on said support between an upward and a downward position, and having a clamping rim for clamping engagement with the border of a hollow enclosure 25 extending around the space in front of said support, a deformed spring wire loop clamped by its outwardly acting spring force against a portion of the inner surface of said clamping member and having a plurality of peripherally spaced inwardly bent portions, a plurality of clamping arms pivotally carried by said inwardly bent portions of said spring member so as to swing freely in radial directions when the clamping member is in its upward position, and a 30 cam member extending from said support having an exposed peripheral cam surface arranged to slidably engage and radially press the inner surfaces of said arms so as to swing them outwardly toward said rim during forward sliding motion of said clamping member on said support, said support, said clamping member, and the associated cam surface and clamp arm elements being so shaped and arranged as to force said arms toward said clamping rim for clamping said enclosure border when said clamping member is in the downward position on said support, and to release said arms from their clamping 35 position and permit the free removal of said enclosure from its clamping engagement when said clamping member is slid toward its upward position on said support.

ALEXANDER K. SUTHERLAND.
